UNITED STATES PATENT OFFICE.

WILLIAM H. GOLDSMITH, OF BERKLEY, RHODE ISLAND.

SWEeper.

SPECIFICATION forming part of Letters Patent No. 501,247, dated July 11, 1893.

Application filed October 18, 1892. Serial No. 449,199. (No model.)

To all whom it may concern:

Be it known that I, WILLIAM H. GOLDSMITH, of Berkley, in the county of Providence and State of Rhode Island, have invented certain new and useful Improvements in Sweepers; and I hereby declare that the following is a full, clear, and exact description of the same, reference being had to the accompanying drawings, forming part of this specification.

10 This invention has reference to improvements in floor sweepers.

The object of the invention is to produce a sweeper which will be adapted to remove lint, or fiber, from bare or carpeted floors.

15 The invention consists in certain peculiar features of construction and novel combination of parts which will hereinafter be more fully described and pointed out in the claims.

Figure 1 represents a view of one form of 20 the improved sweeper formed of flexible sections and having a handle. Fig. 2 represents an enlarged view of a portion of the sweeper-back and wires.

Similar numbers of reference designate corresponding parts throughout.

25 In mills where large quantities of fibrous material are constantly handled lint from the same and also the fiber itself is continually falling on the floor. To remove this lint, or fiber, a thorough sweeping is necessary. This is impractical with the present style of brushes and brooms as the violent movement thereof will raise the light fiber and lint and the drafts occasioned by the movement of the sweepers 30 will drive the fiber and lint over the room where it will cause damage by settling in the bearings of the machinery or on goods in the process of manufacture. Again, in sweeping carpets made of pile fabrics, the ordinary 35 broom or brush will not remove the lint which is caught by the pile. My improved sweeper is designed to overcome these difficulties and

to readily remove lint or fiber from either a bare or a carpeted floor.

In carrying my invention into effect I form 45 the sweeper from several sections of flexible-backings 5-5 through which the wire-teeth 6-6 are inserted. The sections 5-5 I secure together by links 7-7 or any other pivotal fastenings and to one of the sections I fasten 50 the tongue 8 to which any form of handle may be secured. I sometimes secure two or more of the flexible strips, or sections, 5-5, having the bent wires 6-6, to a rigid top 9, Fig. 1, into which a handle may be secured. 55 The backings 5-5 are generally made of leather, but textile material may be used for the same. The wire-teeth 6-6 are of a shape similar to those used in making card-clothing and the improved sweeper may be formed of 60 sections of such card-clothing either when new or when too much worn to be useful in a carding-engine, thus providing a use for this worn-out material which manufacturers have heretofore been obliged to throw away when it has 65 become too much worn to be used in carding-engines.

Having thus described my invention, I claim as new and desire to secure by Letters Patent—

70 1. A sweeper formed of flexible material armed with card teeth and provided with a handle, substantially as hereinbefore set forth.

2. The combination with a plurality, of the sections 5-5 having the teeth 6-6 and secured together by the links 7-7, of the handle-tongue 8 fastened to one of said sections, as described.

75 In witness whereof I have hereunto set my hand.

WILLIAM H. GOLDSMITH.
